UNITED STATES PATENT OFFICE.

ANNA C. LONGFELLOW, OF LARCHMONT, NEW YORK.

REMOVABLE BUTTON.

Application filed January 5, 1926. Serial No. 79,280.

The present invention relates to buttons, and more particularly to a novel form of button adapted to be readily applied to and removed from garments.

5 This application is a continuation in part of my application, Serial No. 4760, filed January 26, 1925.

The primary object of the invention is to provide a button of novel form which is 10 adapted for use on garments such as pajamas, for example, and which may be readily attached to and removed from the garment without sewing, and without the use of metal or other fastening means which would injure the fabric of the garment.

Another object of the invention is to provide a button which may be attached to and detached from a garment and which is made in two parts adapted to be connected in such 20 a manner and is of such form that it may be made readily attachable to and detachable from a fabric connecting means attached to the garment.

A further object of the invention is to provide a button which may be made in parts 25 of such form that one part may be readily inserted in a loop on the garment and the other part connected to the first part in such a way as to hold the loop in place so that the loop forms the connecting means 30 between the assembled button and the garment.

With these and other objects in view the invention comprises the various features 35 hereinafter more fully described and particularly defined in the claims.

The various features of the invention are illustrated in the accompanying drawings showing the preferred form of the invention 40 and means whereby it may be attached to a garment, in which—

Figure 1 is a view of a portion of a garment showing the buttons in place thereon, the views showing also the preferred means 45 for attaching the buttons to the garment, comprising a series of loops, to which the buttons are detachably connected;

Figure 2 is a sectional view taken on the line 2—2 of Figure 1;

50 Figure 3 is a cross sectional view showing the preferred form of my invention and showing the manner in which it may be attached to a loop member;

55 Figure 4 is a sectional view of the button shown in Figure 3 taken on the line 4—4 thereof;

Figure 5 is a vertical sectional view of the button shown in Figures 3 and 4 in slightly modified form;

Figure 6 is a plan view of the base portion of the button shown in Figure 5;

Figure 7 is a vertical sectional view of a second modification of my invention;

Figure 8 is a plan view of the base portion of the button shown in Figure 7 indicating the manner in which the button is to be attached to the garment;

Figure 9 is a vertical sectional view of the cover portion of the form of button shown in Figure 7;

Figure 10 is a vertical sectional view of a third modification of the button showing a form in which the button may be attached to a single strand or cord attached to a garment in place of a loop member, and

70 Figure 11 is a plan view of the form of button shown in Figure 10.

Referring more particularly to the drawings, the numeral 2 indicates a button embodying my invention which is attached to 80 a garment 3 by means of a loop member 4 which comprises the preferred attaching means for the button.

Such loop members 4 may be readily formed on the garment by the use of a fabric member 5 which may be a ribbon or tape and which is attached to the underside of the garment, various portions of the ribbon or tape being passed through a series of slits or eyelets 6 formed in the garment whereby 90 the various loops may be readily adjusted to any desired length. The loops may obviously be formed in any desired manner such as by sewing separate sections of the ribbon or tape in place to form the loops. I may also, 95 if desired, use individual strands for attaching the button to the garment in place of a loop member, such a strand being illustrated in Figure 10, for example.

The preferred form of my invention is illustrated in Figures 3 and 4 in which a base portion or inner portion 7 of the button has a screw thread 8 around its periphery and is adapted to fit a corresponding screw thread 9 in a cover portion 10 of the button. 100 In order to attach the loop member 4, attached to the garment 3, to the button, I preferably provide two lateral slots 11, 12 in the base portion, these slots being preferably located diametrically opposite in the 110 base portion and being of suitable width so that a loop member of sufficient size may be

held in the slots. I preferably employ also a groove in the top of the base portion which connects the slots and has substantially the same width as the slots, thereby permitting the button to slide on the loop member and permitting it to be readily adjusted in place.

By the use of this form of the invention, the button may be readily attached by passing the base portion 7 into the loop member 4 so that the sides of the loop member pass through the slots 11 and 12 in the base portion. By holding the lower end of the loop member between the fingers, the cover portion 10 may then be readily screwed onto the base portion 7 until the cover portion contacts with the top of the base member which will then serve to hold the parts in place.

I may, if desired, employ a stop member on the base portion 7 in place of the groove so that by screwing the base member into the cover portion 10 until the stop member contacts with the under side of the cover portion the loop or connecting member may be held rigidly in place. It is to be understood however, in the preferred form of the invention I do not employ the stop member since this would complicate the construction of the button and add to its cost of manufacture.

In the modified form of button shown in Figures 5 and 6 the construction of the parts is identical with that shown in Figures 3 and 4 except that the base member 7 has a raised portion at its center serving to bind the loop member only at the center of rotation of the base member 7 in the cover portion 10 whereby a binding force will be exerted on the loop member without requiring any substantial additional torsional force to unscrew or separate the parts when the button is in place on a garment.

In the modification shown in Figures 7, 8 and 9, I employ a large base member 7' which preferably has a raised central portion 13 around which is an external screw thread 8' and in which, around the base portion of the raised member 13, I preferably employ a groove 14, around which the loop member 4 attached to the garment may be passed and held in place by means of the cover portion 10' which has an internal screw thread 9' fitting or corresponding to the screw thread 8'. Through the central portion of the base member 7' is an opening 15 which is preferably circular in cross section and which preferably extends entirely through the member. Through one side of the raised portion 13 I preferably cut a slot 16 which extends inwardly and connects with the central opening 15 whereby the loop 4 attached to the garment may be inserted through the central opening and outwardly through the slot 16 and thereafter the loop may be passed around the raised member 13

in the groove 14 which serves to hold the loop member in place as is shown in Figures 7 and 8. After the loop member is in place the cap or cover 10' may be screwed in place, thereby hiding the loop member and the raised portion from view and has the appearance therefore of an ordinary button. In this modification of the button I may extend the slot 16 diametrically through the base portion or if desired the opening 15 might be passed through the base portion and raised member 13 at an angle so as to provide an opening extending from the base 7' through the side of the raised portion 13 whereby the loop, when passed therethrough, may be readily passed around the raised member 13 and put in place in the groove 14, after which the cap or cover 10' may be screwed in place in the usual way. This form of button is particularly applicable to large garments such as coats, from which buttons are generally removed before sending to the cleaners, for example, and the sewing on of the button may, in this way, be avoided. It is obvious that the two parts of the button may be made in different colors so as to obtain a contrast if desired. I might, for example, employ a button having a light green base member and a dark green cover portion or central portion of the button or entirely different colors may obviously be employed for the different parts, if desired.

Another form of button illustrated in Figures 10 and 11 which is particularly adapted for use in connection with expensive garments, in which the buttons may be made in the form of a flower, for example, comprises a base portion 7'' which may be made to simulate the petals of a flower, in which is a central opening 15'' communicating with a larger central opening 17 into which a fastening member or cover portion 10'' is adapted to be screwed in the manner illustrated in Figure 10. This central portion may represent or simulate the central portion or disc portion of a flower and is preferably of a different color from the outer portion representing the petals of the flower, as above stated.

This form of button may obviously be used with a loop member, if desired, by passing the loop through the opening 15'' and clamping or fastening it in place between the base member 7'' and the fastening member 10''. The button is particularly adapted however to be employed with a single strand to fasten it to a garment. Such a strand is shown in Figure 10, the strand being passed through the opening 15'' which is preferably slanted so that the strand when passed therethrough will be in a position to be clamped or fastened in place by the cover or clamping member 10''.

It is obvious that various parts of my in-

vention may be altered or changed without departing from the spirit or scope of the invention as defined in the claims.

Having thus described the invention, what is claimed as new is—

1. A button adapted to be applied to and removed from a garment without sewing, which comprises a plurality of parts adapted to be detachably joined together and to be attached to a fabric member connecting the button with the garment.
2. A button adapted to be applied to and removed from a garment without sewing, which comprises a base member, a second member adapted to be connected to said base member and means to permit connecting the button with a fabric member attached to a garment.
3. A button adapted to be applied to and removed from a garment without sewing, which comprises a base member, a cover member adapted to be connected to said base member and means for holding a fabric member attached to a garment between said cover member and said base member to fasten the said button to said garment.
4. A button adapted to be readily applied to and removed from a garment, which comprises a base portion, an opening in said base portion adapted to receive a fabric member attached to said garment, a second member adapted to be attached to said base portion and to hold said fabric member in place in said opening and means for removably holding said member in place in connection with said base portion.
5. A button adapted to be applied to and removed from a garment without sewing, which comprises a base portion, lateral openings in the said base portion adapted to receive a loop member attached to said garment and a cover portion adapted to be attached to said base portion and to hold said loop member in place in said openings.
6. A button adapted to be readily applied to and removed from a garment without sewing, which comprises a base portion, lateral openings extending inwardly from the periphery of said base portion and adapted to receive portions of a loop member attached to said garment, a cover portion adapted to envelop said base portion to conceal said loop member when the button is attached to a garment and screw-threaded connections between said cover portion and said base member whereby said cover portion may be readily removed from the base portion and to remove the button from the garment.
7. A button adapted to be readily applied to and removed from a garment without sewing, which comprises a base portion, lateral openings extending inwardly from the periphery of said base portion and adapted to receive portions of a loop mem-

ber attached to said garment, a cover portion adapted to envelop said base portion to conceal said loop member when the button is attached to a garment and means in the said button for jamming the said loop member at the central portion of the button, whereby the parts may be readily removed without interference from the fabric member.

8. A button adapted to be readily applied to and removed from a garment without sewing, which comprises a base portion, lateral openings extending inwardly from the periphery of said base portion and adapted to receive a loop member attached to said garment, a cover portion having the form of a button on its exterior side, but adapted to substantially envelop said base portion, screw-threaded connections between said cover portion and said base portion, and a central raised portion on the said base portion adapted, when screwed into place in said cover portion, to bind the said loop member at substantially the center of rotation of said base portion in said cover portion, whereby the said base portion may be readily removed from said cover portion without binding.

9. A button adapted to be readily applied to and removed from a garment without sewing which comprises a base portion, means for connecting the said base portion to a loop member attached to a garment, and means for locking the said loop member in place in said base portion so as to fasten the button to the said garment.

10. A button adapted to be readily applied to and removed from a garment which comprises a base portion, an opening in the said base portion adapted to receive a fabric member attached to the said garment, a cover portion adapted to enclose the said base portion and to hold said fabric member in place in said opening and means for removably holding the said cover portion in place on the said base portion.

11. A button adapted to be readily applied to and removed from a garment without sewing which comprises a base portion adapted to hold a loop member attached to the garment, and a removable cover member adapted to envelop a part of the said base member and said loop when the button is attached to the garment.

12. A button adapted to be readily applied to and removed from a garment without sewing which comprises a base portion adapted to hold a loop attached to the garment, a member adapted to cover the said base portion and loop during use on the garment, and a screw threaded connection between said base portion and said member whereby said member may be readily removed from said base portion.

13. A button adapted to be readily applied to and removed from a garment which com-

prises a base portion, a slot in the said base portion, a member adapted to hold a loop attached to the said garment in proximity to the central portion of said base portion, 5 a cover portion, and means for locking the said cover portion in place on said base portion, whereby the said loop will be held in place on said member.

14. A button adapted to be readily applied to and removed from a garment which comprises a disk portion, means for connecting a fabric member attached to a garment to

the said disk portion, external threads on the periphery of said disk portion, a cover portion for said disk portion, an opening in 15 said cover portion having internal threads therein conforming to the external threads of said disk portion, and means for holding the said fabric member in place when the said cover portion is screwed into place on 20 the said base portion.

Signed at New York, N. Y., this 30 day of December, 1925.

ANNA C. LONGFELLOW.
